BRICK TREATING METHOD AND APPARATUS THEREFOR

George B. Kissinger, Takoma Park, Md.

Application November 2, 1936, Serial No. 108,893

5 Claims. (Cl. 25—135)

The present invention relates to improved kilns and methods of loading, unloading and using the same. More particularly the present invention relates to novel portable kilns for treating ceramic or analogous materials and methods of using the same.

Kilns of the above mentioned character, now in general use, consist of large stationary structures adapted to be loaded and unloaded by workmen entering suitable doors provided in the kiln walls. As a consequence considerable handling of the materials and long cooling periods are necessary in order to load the same. To illustrate, the present practice, where the material treated is brick, requires the transportation of green brick in cars to the buyer, a building consisting of heated chambers, then to the kiln floor where the products are set for burning. Unloading the kiln necessitates placing the finished product on cars or wheelbarrows and transported to storage or delivery trucks. It will be appreciated that extension trackway systems and numerous cars and workmen are required in a plant where a considerable volume of brick is manufactured.

Furthermore, since the green brick is relatively soft, a kiln cannot be filled entirely at one time. As a consequence, the filling of a kiln must be carried out in stages, that is to say a first layer of brick is deposited in the kiln after it has been treated in a dryer where it is stored until it is dry and hard enough to handle without injury to the product. This necessitates a building, underground flues, stacks, tracks, cars and other materials that are subject to repair at all times and is an expense that materially adds to the cost of production. In addition to this cost it requires extra labor charges to operate and maintain.

It is therefore a primary object of the present invention to provide a kiln structure permitting the proper stacking and drying of the green brick in a much shorter time while eliminating the extensive trackways, the numerous cars and the prolonged drying periods.

A further important object of the present invention resides in the provision of a kiln structure which enables the burning of a maximum number of brick with the smallest number of kilns and fire boxes.

A still further object of the present invention resides in the provision of a portable kiln which enables the loading and unloading operations to take place in the open without resorting to frequent rehandling of the brick.

Another object of the present invention re-

5 sides in providing a kiln having a light weight steel frame work and spaced light weight insulating lining blocks for preventing radiation of the heat.

10 Another object of the present invention resides in providing a kiln formed by mating semi-kiln units so that the kiln may be transported from one brick treating station to another with facility.

15 Another object of the present invention is to provide a light-weight kiln that may be transported from one brick treating station to another as a unit.

20 A still further object of the present invention resides in providing a kiln with removable fire boxes and fire arch doors.

Other objects will appear as the description proceeds in connection with the appended claims and attached drawings wherein:

25 Figure 1 is a diagrammatic plan view of a plant embodying the present invention and showing the kilns of the present invention disposed in operative relation with respect to the well known flue connections and the novel arrangement of circulating fans used in the present invention.

30 Figure 2 is a diagrammatic sectional view through one of the kilns illustrated in Figure 1 showing the manner in which the green brick is loaded in the kiln.

35 Figure 3 is a side elevational view in partial section showing a kiln constructed in accordance with the present invention.

Figure 4 is a plan view of the kiln shown in Figure 3.

40 Figures 5 and 6 are detailed sectional views showing the novel manner of securing the insulating lining to the steel frame work of the present invention.

45 Figure 7 is a fragmental view disclosing a damper structure designed to permit chemical treatment of brick to provide flash brick or the like.

With continued reference to the drawings wherein like reference numerals are used to designate the same parts throughout the several figures, the numerals 10 and 11 indicate the well known double, circular flue structure utilized to obtain proper circulation of the hot kiln gases and the compact arrangement of the several kilns. In this connection, it is to be understood that flues 10 and 11 are superposed in the usual manner, the illustration in Figure 1 being resorted to for the sake of clearness.

Suitable dampers 12 and 13 are located one above the other in their respective flues 10 and

11 for controlling the passage of the hot gases through the flues. Exhaust fans 14, preferably four in number located at approximately 90° intervals around flues 10 and 11, are connected to flues 10 and 11 by means of conduits 15 and 16. Dampers 17 and 17a in conduits 15 and 16 control the passage of gases from fans 14 to flues 10 and 11, respectively. Each fan 14 is provided with an outlet stack 13 and a louvre 19 which is adapted to admit cool air and water into fans 14 for tempering the hot waste gases circulated thereby. Fans 14 are designed to circulate the waste gases through flues 10 and 11 in a manner to be hereinafter described.

Suitable dampers 20 are provided for closing stacks 18 of fans 14. Dampers 12, 13, 17 and 17a are adjustable so that the circulation of the gases may be readily controlled at any point around flues 10 and 11.

A plurality of kiln stations 21 are provided around flues 10 and 11. Stations 21 are preferably equally spaced around flues 10 and 11 and are alternately disposed with respect thereto. In the illustrated embodiment of the invention, fifteen stations spaced at approximately 20° intervals around flues 10 and 11 are provided. As seen in Figure 1, a substantial space is left between the lowermost stations 21, this space being taken up by a loading conveyor 22 for feeding green material to the center of the stations and a shiftable conveyor 22a designed to supply green material to stations 21. The conveyor 22a, as shown in dotted lines in Figure 1, may be brought into operative relation with each of the stations for the purpose of loading the green material. Due to this novel structure any kiln may be loaded at any time since the conveyor 22a may be brought into the desired position irrespective of the position of the kiln to be loaded. Any suitable conveyor structure capable of operating in the above described manner may be used.

Each station 21 is provided with conduits 23 and 24 each of which is connected to flues 10 and 11, and to the center and periphery of the stations 21. Suitable adjustable dampers 25 and 26 control the passage of gases through conduit 23 from the flues 10 and 11 to stations 21. Damper 25 controls the passage of the gases in conduit 23 to or from the center of the stations 21 and damper 26 controls the passage of the gases in conduit 23 to or from the periphery of the stations 21. Dampers 12 and 13 disposed in flues 10 and 11 adjacent dampers 25 and 26 permit the gases in flues 10 and 11 to be directed past dampers 25 or 26 or into conduit 23 in accordance with the desired manner of flow. Dampers 25a and 26a connected in the same manner as corresponding dampers 25 and 26 control the passage of gases from flues 10 and 11 through conduit 24 while the previously described dampers 12 and 13 which are located between dampers 25 and 25a and 26 and 26a respectively permit the gases to be directed past members 25a and 26a or into conduit 24 as may be desired.

As heretofore pointed out, the present invention provides fifteen kiln stations each of which, in the practice of the present improved method of use, functions successively as a loading station, a drying station, a water-smoking station, a pre-heating station, a burning station, a cooling station and an unloading station. In order to more efficiently utilize stations 21 in the several different capacities mentioned, the present invention provides novel portable kiln structures 27. Only twelve kilns 27 are required in the fifteen

kiln stations shown, as hereinafter pointed out.

Kilns 27 may be of any suitable construction, although they are preferably constructed in the following manner to assure more efficient and ready operation of applicant's novel method of operation. Kilns 27 made in accordance with the present invention comprise vertical wall sections 28, and sloping wall sections 29 and 31.

Sections 28 are identical in construction except for the end half wall sections 32 of each semi-kiln unit 33 and as a consequence only one will be described in detail. Section 28 includes a pair of spaced vertical I-beams 34 preferably of steel. I-beams 34 are interconnected adjacent their upper ends by a relatively short horizontal steel I-beam 35. A pair of vertical U-frame members 36 are disposed in spaced relation on opposite sides of I-beams 34. Members 36 adjacent their upper ends are connected to I-beams 34 by I-beams 35 identical to the I-beams 35 previously described. As seen in Figure 3, members 36 of adjacent sections 28 are in abutting engagement in order that adjacent wall sections 28 may be intimately joined together. Short I-beams 37 interconnect I-beams 34 and frame members 36 as seen in Figure 7. I-beams 37, as seen in Figure 3 are of slightly less depth than I-beams 35 for a purpose that will presently appear. The ends of I-beams 35 and 37 are preferably welded to I-beams 34 and frame members 36, although any other suitable connection may be employed.

The lower ends of I-beams 34 and members 36 are interconnected by a U-frame member 38 which is disposed with its flat surface facing downwardly. The upper ends of I-beams 34 and members 36 are interconnected by a U-frame member 39, the longitudinal flanges of which are vertically offset so as to cause its flat surface 40 to slope downwardly away from the outer exposed face of I-beam 34. The slope of surface 40 may assume any desired angle, but a 45° angle as illustrated is preferably used.

A flat sheet steel plate 41 is secured to the outer exposed faces of I-beams 34, 35 and 37 and frame members 36, 38 and 39 by bolt and nut assemblies 42 including compressible washers 43 adapted to permit expansion and contraction of the joints as the temperature in kiln 27 is raised and lowered. Plate 41 is provided with a fire arch 44 which extends upwardly from the flat surface of U-member 38 to a point just below I-beams 35. In order that arch 44 will be unobstructed at the bottom the upwardly extending flanges 45 of member 38 are omitted between the I-beams 34. The vertical edges 46 and 47 of plates 41 on adjacent sections 28 overlap each other as seen in Figures 4 and 5.

In the preferred embodiment of the invention four wall sections 28 are placed in position with their frame members 36 in mating engagement. Bolts 48 are provided with compressible washers 49 and nuts 51 are utilized to secure the sections together in such a manner that the necessary expansion of the sections may take place. The edges of the end sections 28 are then provided with a half wall section 32 which is formed in the same manner as a half of wall section 28. The exposed edge 52 of section 32 is formed by a U-frame member 53.

The complete vertical wall of kiln 27 is formed by placing the frame members 53 of semi-kiln units 33 in abutting engagement and securing them together by expansion bands 54 and 55. Bands 54 preferably take the form of short sections 56 having integral outwardly extending

flanges 57 formed at their opposite ends. Flanges 57 of adjacent sections 56 are connected together in such a manner that expansion is permitted between the ends of the adjacent sections.

Expansion band 55 is made up of short sections 56 like those previously described and sections 58 having flanges 59 at their ends. One flange 59 is connected to flange 57 of section 56 in the same manner previously described in connection with flanges 57 while the other flange 59 is adapted to be connected to removable fire boxes 61 or to fire arch doors 62 when fire boxes 61 are not in place.

As seen in Figures 3 and 4, wall sections 29 which are identical are formed by members 65 of a length equal to that of members 39 of sections 28 and spaced parallel members 66 approximately half the length of members 65. The ends of members 65 and 66 are connected by U-shaped frame members 67 and the outer exposed surfaces are covered with steel plates 68. Members 65 and 66 of adjacent sections 29 and 31 are in abutting engagement so that members 39 and 65 may be secured in intimate jointed relationship and members 66 may likewise be connected to members 66 of sections 31. Since members 66 are shorter than members 65, sections 29 are wedge-shaped, the smaller end being disposed nearest the center of kiln 27. Suitable bolts similar to bolts 48 secure sections 29 to sections 27. Half sections 69 made up like half of a section 29 are provided for connection to sections 32 of the vertical kiln wall. Sections 69 are provided with centrally disposed U-shaped frame members 71 corresponding to frame members 53 of sections 32.

Sections 31 are formed in exactly the same manner as sections 29, the only difference being that the parallel U-shaped frame members are shorter, i. e., the longest member 66 is exactly equal to member 66 of section 29 and the shorter member 72 is materially shorter. U-frame members 67 interconnecting the ends of members 66 and 72 and plates 68 complete sections 31. Sections 31 are connected to sections 29 by bolts similar to bolts 48 in a manner that will be clearly understood.

As a consequence, sections 31 appear as extensions of sections 29 when viewed from above, as seen in Figure 4, and extend nearly into abutting relation with each other at the center of kiln 27. The small space left between members 72 or sections 31 is closed by a plug-like member 73. Member 73, due to the fact that ten wall sections 28, 29 and 31 are used in the illustrated embodiment of the invention is of a decagonal shape. Member 73 is connected to sections 31 in the same manner that the several sections 28, 29 and 31 are connected to each other. Suitable vents 74 are provided in sections 31 for a purpose to be hereinafter pointed out.

The various I-beams, U-shaped frame members and plates are preferably made as light as possible consistent with the requisite strength of the steel supporting framework. As consequence, the entire framework assembly is relatively light in weight.

The steel framework constructed in the above mentioned manner is then lined with heat and fire resistant material. This material preferably takes the form of siliceous blocks, slabs, strips or the like indicated by numeral 75. As seen in Figure 3, the lowermost portion of wall sections 28 are of double thickness, the innermost layer 76 being fire brick in order to withstand the knocks and rough treatment usually encountered 75

at this point. It is for this reason that I-beams 37 are of less depth than I-beams 35.

While lining members 75 are preferably made of siliceous material due to its relatively light weight and high heat and fire resistant qualities, it is to be understood that any other material exhibiting the desired characteristics may be employed. Members 75 are so mounted that they entirely cover the inner surface of kiln 27. Due 10. to this fact radiation of heat is prevented and the steel framework is subjected to the least possible amount of heat and is shielded from the flames.

In order that members 75 and 76 may be mounted as desired, applicant provides lowermost members 76 of sections 28 with a recess 77 which fits over the inner upstanding flange 45 of frame member 38 and recesses 78 which engage behind the flanges of members 34 and 36. The flat surface 79 of the member 75 abuts the 20 inner flange of member 37 thereby holding member 75 in place.

The remaining members 75 and members 76 are held in place by a novel anchor rod construction as seen in Figures 5 and 6. Referring to these figures, it will be seen that dove-tail grooves 81 are provided in these members. Grooves 81 are designed to receive dove-tail formations 82 which are formed around the central straight portions 83 of anchor rods 84. Rods 84 at their ends are offset at 85 to provide hook elements 86 which engage the rear surfaces of the flanges on members 34 and 36. As seen in Figure 5, members 75 adjacent the ends of rods 84 extend beyond hook elements 86 and fit against the opposite faces of the flanges provided on members 34 and 36. The same is true of members 76 provided on sections 28.

Rods 84 are made of a length sufficient to insure the proper disposition of hooks 86 with respect to members 34 and 36. Members 75 are then slipped over dove-tail formations 82 and the rod with the necessary number of members 75 thereon is placed in position with respect to members 34 and 36. Members 75 are associated with members 67 of sections 29 and 31 in the same manner until the entire interior surface of kiln 27 is suitably lined.

After members 75 are in place the interior surface thereof is coated with fire resisting compound of any suitable character indicated by numeral 87. Compound 87 seals the crevices between members 75 and the joints between the adjacent sections 28, 29 and 31. Compound 87 is also used to cover the abutting end surfaces of semi-kiln units 33 to seal the joint between these units. The space 88 between plates 41 and members 75 is preferably filled with granular insulating material 89 of any suitable character or if desired, material 89 may be omitted and air 60 circulated through space 88 to prevent the metal frame-work from reaching a high temperature.

In view of the fact that a light-weight framework structure is employed in conjunction with light weight siliceous lining material the completed kiln 27 is very light. As a consequence, the semi-kiln units 33 may be moved around with great dispatch on rollers 91 provided on jacks 92 which are connected to suitable lugs 93 secured to plates 41. Jacks 92, as illustrated in Figure 3, are extensible in order to raise semi-kiln units 33 so they will clear the floor surface of the kilns when it is desired to move the units.

If desired kiln 27 may be raised as a unit by means of a suitable crane connected to lugs (not

shown) secured to the plug member 73 and the kiln sections 31, and bands 54.

Fire boxes 61 and fire arch doors 62 previously described are removably connected to kiln sections 29 by means of lugs 94 secured in any suitable manner to fire boxes 61 and doors 62 and adapted to be connected to plates 41 adjacent arches 44. Fire-boxes 61 and doors 62 are preferably lined with members 76 in the same manner as kiln sections 28, and the joint between fire-boxes 61 or doors 62 and sections 29 is sealed with compound 87 in well known manner.

Operation

The operation of the illustrated fifteen station kiln system is as follows:

Assuming for purposes of this description that station A is to be supplied with an initial charge of green brick and that stations B, C, and D are drying stations having varying fractions of their total charge of brick; that station E is the water-smoking station, at a temperature of approximately 400° F.; that station F is the pre-heating station, at a temperature of approximately 800° F.; that stations G, H and I are burning stations, at temperatures of approximately 1200° F., 1600° F. and 1800° F., respectively; and that stations J, K, L, and M are cooling stations, at temperatures of approximately 1600° F., 1200° F., 800° F. and 400° F., respectively; and that stations N and O contain the finished products and are without kilns 27; that station A is without a kiln; green brick is deposited on conveyor 22 and conveyed to station A, where it is stacked in proper manner on the floor. During this stacking operation kiln units 33 at station M are transferred to station A and positioned about ten feet apart so that conveyor 22 may swing back and forth in well known manner. The dampers 25, 25a, 26 and 26a at station A are closed at this time to prevent gases in flues 10 and 11 from entering conduits 23 and 24 and dampers 12 and 13 are open to permit free passage of gases past station A. Since the green brick is relatively soft a portion only of the ultimate final quantity of brick may be stacked at one time. In this connection, it has been found that approximately one-fourth of the total number of brick, as indicated by dotted line a—a in Figure 2, may be stacked at this time.

After the desired quantity of brick is positioned at station A semi-kiln sections 33 are brought into abutting engagement by means of jacks 92. Since it is only necessary to dry the brick at stations A, B, C, and D, a sufficient amount to raise its mechanical strength to a point enabling the stacking of additional brick thereon, a relatively low temperature is satisfactory. As a consequence, the waste heat from the cooling kilns at stations J, K and L tempered to proper temperature and water content by cool air and water admitted through louvre 19 at the fan 14 adjacent station M are preferably utilized, thereby eliminating the necessity of firing the kilns at stations A, B, C, and D. As a consequence the kilns at stations A, B, C and D are provided with fire arch doors 62 instead of fire boxes 61. The number of fire boxes 61 required can therefore be reduced since they are removable and interchangeable with doors 62. This enables reduction of the equipment cost by the difference between the cost of forty fire boxes and forty fire arch doors. This reduction in cost when added to the saving effected by the elimination of three kilns, due to the fact that no kilns are required

at stations M, N and O, materially reduces the cost of equipping and maintaining a treating plant in operation. It, of course, will be understood that fire arch doors may be designed to close the openings through fire boxes 62 and the full number of fire boxes used without departing from the present invention.

In order to circulate the gases through kilns 27 at stations A, B, C and D in the desired manner and properly temper the gases, the dampers in flues 10 and 11 and at stations A to D and I to L and the dampers at fans 14 adjacent stations A and M are positioned as shown in Figure 1 and the fans 14 are started, the fan at station A creating a suction in flue 11 and the fan at station M drawing cool air and water through louvre 19 and forcing it into flue 11. Dampers 20 provided in fans 14 at stations A and M are, of course, closed at this time to prevent escape of the gases through stacks 18.

As a result of this arrangement of dampers and fans, the hot gases from the kilns at stations J to L are drawn from the cooling kilns into flue 11, due to the action of fans 14 at stations A and M, and tempered and forced through flue 11 in a clockwise direction as indicated by arrows R, to damper 13 at station A. At this point the gases divide into three streams one passing into and through the kiln at station A and out through vents 74, another passing by damper 13 and on to the kiln at station C and through vents 74 at station C and the third being drawn through fan 14 at station A and forced into and along flue 10 into the kilns at stations B and D and out through the vents 74. In each instance the gases are directed into the center of the kilns and up through the material and out through vents 74. The tempered gases passed through the kilns at A, B, C and D are preferably at a temperature of approximately 300° C. and are circulated by the action of the fans 14 at stations A and M. The suction action of fan 14 adjacent station A is, of course, regulated so that only a portion, preferably one-half of the gases in flue 11 are circulated therethrough.

Since the two fans 14 that are in use in circulating these gases are relatively close to the cooling and loading kilns, a strong circulation of the gases through flues 10 and 11 and kilns A, B, C and D is obtained. If desired, fan 14 at station M may be relied upon to circulate the gases through flue 11 to stations A, B, C and D the fan at station A being cut off and damper 13 opened.

Simultaneously with the circulation of the gases from the stations J to L to stations A to D, the hot gases in the burning kilns at stations G to I are drawn into and through flue 10 in a counter-clockwise direction, as indicated by arrows T, by fan 14 adjacent station E and passed through the pre-heating and water-smoking kilns at station F and E, respectively. In order to effectively circulate these gases, damper 12 adjacent station F is partially closed so as to divide the gases into two streams. One stream passes through conduit 23 into the center of the kiln at station F and up through the stacked brick, then down into the peripheral flue and out through conduit 24 into flue 11, through flue 11 and into fan 14 at station E where it is exhausted into the atmosphere. The other stream passes damper 12 and enters flue 23 and the kiln at station E and circulates therethrough in the manner described in connection with the kiln E at station F. After passing through station E

these gases enter flue 11 and are exhausted through fan 14 at station E along with the gases from station F. A strong circulation of gases is obtained here also due to the proximity of fan 14 to the kilns E to I.

In view of the fact that the hot gases from the burning kilns contain sulphur and other undesirable constituents which would harmfully affect the green brick at the loading stations should the gases reach the green brick, it is necessary to provide means for preventing the passage of these gases through the loading kilns. In the present invention this end is obtained by closing the dampers 12 and 13 between the burning kilns and the cooling kilns and between the water-smoking kiln and the loading kiln. It will, accordingly, be appreciated that the present invention provides independent paths for the gases to prevent injury of the brick in the manner pointed out above.

This circulation of gases is preferably maintained for twenty-one and one-half hours, i. e., a full twenty-four hour day minus two and one-half hours, the time necessary to place one-fourth of the total quantity of brick in position at stations A, B, C and D. After completion of this first full day's treatment conduits 23 and 24 at stations A to D are shut off by means of dampers 25, 25a, 26 and 26a and a further charge of brick, preferably one-fourth of the total brick to be treated at stations A to D is loaded. At the same time the next station, station O, which has been unloaded, is supplied with its initial one-fourth charge and the kiln 27 at station L, the coolest of the cooling kilns is transferred to station O.

The various dampers are then adjusted in order that the gases from the new cooling kilns I to K are circulated in a clockwise direction through flue 11 and then through the new loading kilns O, A, B and C while the gases from the new burning kilns F to H are circulated in a counter-clockwise direction through flue 10 into the new pre-heating and water-smoking kilns at stations E and D, respectively. After another twenty-one and one-half hour heating period the final one-fourth of the brick is placed at station B, the third one-fourth of the brick at the station A, the second one-fourth of the brick at station O, and station N, which has now been unloaded, is supplied with its initial one-fourth charge. This progressive operation of loading and unloading is continued indefinitely, stations A to O each becoming loading stations, water-smoking stations, pre-heating stations, burning stations, cooling stations, etc., in succession.

It will be noted that fire boxes 61 are not connected until a particular station becomes a water-smoking station. In other words, the heat used for the initial drying of the brick in all four stages of loading is obtained from the tempered waste gases from the cooling kilns and the water-smoking station derives its heat from the gases from the burning stations, although fire boxes 62 are in place ready for firing in order that the desired temperature of approximately 400° C. may be maintained. Fire boxes 62 are usually, however, fired at the pre-heating station and remain in operation until the kiln has reached the position in the cycle of operation corresponding to the first cooling station where the fire is drawn. Fire boxes 62 are transferred from the third cooling station to the kiln at the water-smoking station and the fire arch doors at the water-smoking station are transferred to the

75 kiln at the third cooling station in order that the desired saving in equipment may be effected.

Occasionally it is necessary to speed up the burning of the brick at the last burning station 5 in order to assure proper treatment of the brick. The present invention is peculiarly adapted to take care of such an emergency since it is only necessary to increase the draft in the particular kiln by operating the fan 14 nearest the kiln 10 in question. For example, we shall assume that the kiln at station I during the first day's run described above needs to be speeded up. This may be accomplished by closing damper 25 at station I and opening damper 25a and dampers 15 17 and 17a in conduits 16 and 15, respectively at fan 14 adjacent station I. Fan 14 will then act upon the kiln at station I and draw the gases from the center of the kiln through conduit 24 and conduit 16 of fan 14 and push the gases 20 back through conduit 15 of fan 14 into flue 10. As a consequence a much stronger draft is obtained at station I and a hotter fire in fire boxes 62 is obtained.

By use of the removable kilns, fire boxes, fire 25 arch doors and the practice of the method just described, a considerable saving in loading and treating time is effected. This saving results from the fact that the loading and setting of the kilns can be accomplished in rapid succession since it is not necessary for the workmen to enter the kilns in order to load them. This saving is obtained since kilns 27 themselves are moved from around the stack of brick so as to enable the loading of the kiln in the open air. 30 As a consequence the loading and setting of the brick requires only four days. Since the water-smoking treatment requires one day, the pre-heating one day, the burning three days, the cooling four days, the final cooling and unloading 35 two days, it will be seen that the complete cycle of operations to obtain the finished brick requires just fifteen days. Due to this fact, it will be appreciated that the preferred embodiment of the invention provides a very simple and efficient continuous treating cycle.

In order that a flash brick or other chemically treated brick may be formed in the present system the additional damper structure shown in Figure 7 is preferably provided. Referring to 50 Figure 7 dampers 77 and 78 are provided to close off conduits 23 and 24 between the kiln and dampers 25, 25a, 26 and 26a and a damper 79 is provided in the partition wall between conduits 23 and 24. With dampers 77 and 78 closed and damper 79 opened the gases in flues 10 and 11 may be by-passed around the kiln and the desired chemical supplied to the kiln. As a result of this structure the chemical may be supplied at the proper time without interfering with the normal operation of the remaining kilns.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for use in treating ceramic or analogous material comprising in combination

one or more circular flues; a plurality of kiln stations located at spaced intervals around said flues, said stations being alternately arranged with respect to said flues; and a plurality of movable kilns of lesser number than said stations positioned at successive stations to cover the same, thereby leaving certain stations uncovered whereby said kilns may be moved from the final one of said covered stations to the uncovered station adjacent the initial covered station as the treating process proceeds.

2. The apparatus defined in claim 1 wherein each of said kilns is made in at least two units, each unit having jacks connected thereto for facilitating movement of said units.

3. The method of treating ceramic or analogous material in a multiple kiln brick manufacturing plant having a plurality of treating stations and a lesser number of covers for forming the complete kilns, comprising the steps of stacking a portion of the total charge of material in position for treatment at an unloaded station, covering said stacked material, passing tempered waste gases from cooling kilns through said material and through the partially dried material at the drying stations next succeeding said first mentioned station, passing untempered waste gases from the final burning kiln through said dried material at the last previous drying station for water-smoking said material, firing the material at the station next succeeding said new water-smoking station to pre-heat said material, maintaining and increasing the fire at the stations next after the new preheating station to burn the material at said stations, withdrawing the fire from the material at the previous final burning station to permit cooling of the material, admitting air through the fire openings at the station next succeeding said new cooling station, uncovering the material at the next succeeding cooling station to permit final cooling of the material in the open, unloading the completed material at the next succeeding station and stacking a portion of a further total charge of material at said last-mentioned station after unloading and repeating the aforementioned steps so as to successively alter the character of the treatment at each station as long as the plant is to be operated.

4. The method of treating ceramic or analogous material to harden the same comprising the steps of stacking a portion of the material, completely enclosing the stacked material with kiln sections, preliminarily drying said stacked material to partially dry it by passing tempered waste gases from cooling kilns through the material, completely removing said kiln sections to allow free circulation of air through the partially

dried material whereby the harmful gases are rapidly dissipated to permit the stacking of further green material, stacking further portions of said material, again enclosing the material with the kilns and preliminarily drying the same, passing untempered waste gases through the material to effect water-smoking and aid pre-heating of the material, firing said material to apply direct heat to said material for pre-heating, increasing the firing of the material to burn said material, withdrawing the fire from said material after completion of the burning to permit preliminary cooling of said material, admitting air to said material to substantially complete cooling of said material and uncovering said material to permit final cooling.

5. The method of treating ceramic or analogous material such as brick to obtain finished brick by means of a continuous fifteen-day treating process, comprising the steps of stacking one-fourth of the full charge in position to be treated, completely enclosing said partial charge with kiln sections, passing tempered waste gases from cooling kilns through said materials for approximately twenty-four hours, completely removing said kiln sections from said partial charge to allow free circulation of air through the partially dried material whereby the harmful gases are rapidly dissipated to permit the stacking of further green material and stacking a second one-fourth of the full charge upon said first-mentioned one-fourth charge, completely enclosing said partial charges with said kiln sections and passing said tempered waste gases through said partial charge for approximately twenty-four hours, repeating said steps until the several one-fourth charges are partially dried and the last one-fourth of the full charge has been subjected to said tempered gases for approximately twenty-four hours, then passing untempered waste gases from a burning kiln through said material for twenty-four hours to effect water-smoking and through said water-smoked material while firing said material for twenty-four hours to pre-heat said charge, increasing the firing of said material for seventy-two hours to effect burning of said charge, withdrawing the fire from said material and allowing forty-eight hours to effect partial cooling of said charge while covered and without admission of external air, permitting ingress of external air to the covered material for a further twenty-four hours to effect further cooling of said charge completely removing said kiln sections from said material and permitting material to cool for forty-eight hours in the open to complete the cooling and removing said material to a storage room or to any other desired point.

GEORGE B. KISSINGER.
